UNITED STATES PATENT OFFICE.

GEORGE W. MCGILL, OF NEW YORK, N. Y.

DESIGN FOR A DRAPERY-HOOK.

SPECIFICATION forming part of Design No. 22,820, dated October 3, 1893.

Application filed September 9, 1893. Serial No. 485,197 Term of patent 14 years.

To all whom it may concern:

Be it known that I, GEORGE W. MCGILL, a citizen of the United States, residing at Riverdale, New York, in the county of New York, State of New York, have invented and produced a new and original Design for Drapery-Hooks, of which the following is a specification.

This design has for its object to provide a novel, ornamental and decorative metallic drapery hook for hanging curtains, portières and similar drapery, and consists of a hook composed of a piece of round wire bent in shape somewhat like a capital **S**, one end being pointed and free and the other end provided with an integral lateral angular extension to which is permanently affixed a metal head fashioned to represent a fleur-de-lis.

The design is illustrated by the accompanying drawings in which—

Figure 1 represents a plan view of the upper and embossed surface of the fleur-de-lis shaped head of the device and part of the upper fold of its hook, and presents in dotted lines the position on its under surface of its integral collar and the lower part of the hook. Fig. 2 represents a vertical sectional view of the device taken on line 2 of Fig. 1.

In the drawings the numeral 1 indicates the fleur-de-lis shaped head of the device having its upper surface fashioned in relief and the numeral 2 indicates the **S** shaped hook of the device.

Numeral 3 indicates the under surface of the fleur-de-lis shaped head provided with a

projecting integral hollow collar 4 in which the angular extension 5 of the hook is permanently secured, and holding the hook proper in position in a plane with the vertical axis of the fleur-de-lis shaped head, the free or pointed end of the hook facing outward.

Numeral 6 indicates the lower folded section of the hook forming its drapery riding saddle, and numeral 7 indicates the upper folded section of the hook forming its pole-ring riding saddle.

The numeral 8 indicates the dependent free pointed and penetrating end of the hook in position and closing the folded upper section 7 of the hook by being in spring contact with the diagonally bent body-part 9 of the same.

The design provides a novel and ornamental decorative drapery hook which presents a striking and characteristic appearance.

What I claim is—

The design for a metallic drapery-hook having a head shaped to represent a fleur-de-lis, its upper surface fashioned in relief and extending from its under surface an **S** shaped wire-hook, substantially as shown and described.

In testimony whereof I have hereunto set my hand and affixed my seal in the presence of two subscribing witnesses.

GEORGE W. MCGILL. [L. s.]
